UNITED STATES PATENT OFFICE.

ELIZABETH BAILEY SPRAGUE, OF SPOKANE, WASHINGTON.

DESIGN FOR A STOVE-LEG.

42,652.

Specification for Design.

Patented June 18, 1912.

Application filed February 27, 1912. Serial No. 680,329. Term of patent 14 years.

To all whom it may concern:

Be it known that I, ELIZABETH BAILEY SPRAGUE, a citizen of the United States, residing at Spokane, in the county of Spokane, State of Washington, have invented a new, original, and ornamental Design for Stove-Legs, of which the following is a specification, reference being had to the accompanying drawing, forming part thereof.

The figure is a perspective view of a stove leg showing my new design.

I claim:

The ornamental design for a stove leg as shown.

ELIZABETH BAILEY SPRAGUE.

Witnesses:

EDW. B. NELSON,
EDITH SPRAGUE.
